UNITED STATES PATENT OFFICE.

L. C. ENGLISH, OF CORNING, NEW YORK.

IMPROVEMENT IN STUMP-EXTRACTORS.

Specification forming part of Letters Patent No. 58,235, dated September 25, 1866.

To all whom it may concern:

Be it known that I, LUZON C. ENGLISH, of Corning, in the county of Steuben and State of New York, have made new and useful Improvements in Stump-Extractors; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which—

Figure 1 is a front elevation, and Fig. 2 is a side elevation. Fig. 3 is a sectional view through the foot C.

The improvement consists of a vertically-extensible derrick-frame, from which the hoisting apparatus is suspended, the frame being provided with an adjustable brace.

It also consists of an adjustable foot to one support of the frame.

In the drawings, A A are the front supports of the derrick, and B the back support, of which the foot C is pivoted so as to be adjustable in a horizontal plane. The brace D connects the standards A A and B, and is vertically adjustable, as shown in red lines, Fig. 2, as the foot C becomes partially embedded in the ground under the pressure brought thereon in lifting the stump and tearing it loose from the earth. The brace has a block, E, whose face agrees with the edge of the standard B, at the different inclinations it assumes, and a catch, e, enters a notch in the edge of the standard to maintain the required relative position.

Suspended from the bolt which forms the point of junction for the standards A A and B, is a frame, F, carrying two sheaves or pulleys, over which the chain G passes, as it does also over the sheaves in the lower frame H, whose lower end has hooks I I, which form means for attachment of the stump-chain J, which is wrapped around the stump or inserted under one of the main roots, as circumstances may render convenient.

The chain J, passing upward and over a pulley, K, descends and winds around chain-roller L, which is rotated by the gear-wheel

M and the pinion N, the latter being on the secondary shaft O, which is rotated by the drawing upon the cord P on the drum R.

To the end of the cord or rope P a horse may be attached, and as he draws upon the line a very great power is exerted upon the stump-chain J.

If the line be all unwound before the requisite lifting is effected, the secondary shaft-pinion is thrown out of engagement with the gear-wheel M, when the latter being retained by the pawl S, the shaft O is rotated in the contrary direction and the rope rewound upon the drum R, the parts occupying the position shown in red lines in Fig. 1.

When the shaft O is in its position for lifting, the clutch T is down and maintains the shaft O in place, but when the clutch T is lifted the shaft O may be slipped along longitudinally for the purpose expressed.

When a great strain is brought upon the derrick, the feet spread and sink in the soil, which brings a great tension upon the brace and lateral strain on the supports A A B, which is apt to fracture them. At such times by lifting the catch e and allowing the block E to raise on the support B, the lateral strain on the supports is relieved and the danger avoided.

The machine being put up in a field and the supports locked together by the brace and catch, it may be hauled about the field to different points without taking it down or to pieces.

The foot C has a semi-spherical cup or hollow on its upper surface, which receives the rounded end of the leg B, the leg and the foot being retained in conjunction by the bolt and nut b d, the surface h of the hemispherical protuberance on the lower end of the leg B playing in the recess of the foot as the latter is adjusted to suit the inclination of the ground.

Having described my invention, what I claim therein as new, and desire to secure by Letters Patent, is—

1. The derrick-frame A A B, jointed at its upper end, and provided with an adjustable brace, as and for the purpose described.

2. In combination with the derrick-frame A A B, the pivoted foot at the end of the leg B of the frame, as and for the purpose described.

3. The block E and catch e, so arranged as to render the brace adjustable to the angle formed by the supports A A and B,

and avoid a breaking-strain on the supports, as described.

L. C. ENGLISH.
